DB-324. OR D16,391 EX

DESIGN.

—o—
W. C. HANNA, Jr.

STABLE HINGE.

No. 16,391.

Patented Nov. 24, 1885.

UNITED STATES PATENT OFFICE.

WILLIAM CAMERON HANNA, JR., OF NEW YORK, N. Y., ASSIGNOR TO J. W. FISKE, OF SAME PLACE.

DESIGN FOR A STABLE-HINGE.

SPECIFICATION forming part of Design No. 16,391, dated November 24, 1885.

Application filed May 21, 1885. Serial No. 166,325. Term of patent 7 years.

To all whom it may concern:

Be it known that I, WILLIAM C. HANNA, Jr., of New York, in the county of New York and State of New York, have invented a Design for Stable-Hinges, of which the following is a specification.

My invention consists in a novel design for stable-hinges, as hereinafter more specifically described.

10 The accompanying photograph is a face or front view of a hinge embodying my design.

Heretofore strap-hinges have usually been made with plain surfaces, and when ornamented the ornaments have generally consisted of projections at the sides, formed in various fancy curves or shapes.

20 The leading feature of my design consists in figures formed on the strap or straps of the hinge, representing portions of a horse's harness, thereby producing not only a highly-ornamental design, but one that is also indicative of the use or purpose for which the hinge is designed.

In the photograph, A represents the shorter 25 strap or arm of the hinge, and B the longer one. As shown, each of these arms A and B are representations of a tug or strap with a stitched edge or border, e. The arm A has on

it a central circular plate, E, in the center of which is the figure of a horse's head, I. On 30 opposite sides of this I make the representation of a bridle-bit, D, and beyond these, on either side, I make the figure of a buckle, C, with their tongues protruding through holes o in the arm A, as the same would appear if 35 there were buckles applied to a tug or strap in actual use. The central boss or plate may be made with or without the border shown, and, if desired, the figures representing the bridle-bits may be omitted without affecting 40 the general or main characteristic of the design, which consists of the raised figures representing a harness-strap with buckles on it, with a central boss having the figure of a horse's head thereon.

45 What I claim is—

The design for a hinge herein shown and described, the same consisting of figures representing a strap with buckles on it and a central boss with the figure of a horse's head 50 thereon.

WILLIAM CAMERON HANNA, JR.
